VAPOR ARC LAMP STARTING APPARATUS

Filed July 20, 1925

UNITED STATES PATENT OFFICE

LEBOY J. BUTTOLPH, OF GRANTWOOD, NEW JERSEY, ASSIGNOR TO GENERAL ELECTRIC VAPOR LAMP COMPANY, OF HOBOKEN, NEW JERSEY, A CORPORATION OF NEW JERSEY

VAPOR-ARC-LAMP-STARTING APPARATUS

Application filed July 20, 1925. Serial No. 44,746.

The present invention relates to the starting and operating of vapor electric apparatus, particularly to essential apparatus for starting high potential quartz lamps.

5 The particular object of the present invention is to provide a quartz arc tube of commercial type provided with circuits and mechanism insuring the ready starting of the tube into operation, and to provide improvements in the structure of the tubes.

10 It has been common practice to start mercury vapor lamps having one or more liquid electrodes by tilting the lamp to make and break the metallic connection within the tube.

15 Under certain commercial conditions the tilting of the tube is inconvenient, and I have found it desirable to provide such lamps with a mechanism for heating one of the liquid electrodes until a conducting circuit has been 20 established. This is a more or less lengthy operation, and I have discovered that by combining with the heating mechanism a mechanism for supplying a high potential kick across the terminals of the device while 25 the heating mechanism is working on one of the liquid electrodes the starting of the arc tube into operation is facilitated.

For example, with a quartz arc tube having 30 a solid anode of tungsten and a cathode of mercury and designed to operate on 600 volts, starting by the tilting method is not desirable, due to the fact that the breaking of the heavy arc in the tube causes blackening of the transparent container, and the rush 35 of current is so great as to require complicated auxiliary apparatus to take care of it at the instant of starting. Accordingly, to avoid the deleterious effects of the sudden rush of current through the tube on starting, 40 and to avoid the use of a multiplicity of relays in the auxiliary mechanism I have provided the tube with a heating mechanism for heating the liquid electrode quickly and by providing mechanism for applying a high 45 potential kick across the terminals while the heating mechanism is working I am enabled to start the lamp into operation quickly and at the same time gradually distribute the starting period over a safe interval of time, 50 10 seconds for example, this interval of start-

ing time being found sufficient to permit the tube and its operating mechanism of the simple and usual type well known in the art to take care of the heavy current passing through the quartz arc tube.

55 In the accompanying drawing I have illustrated my invention in connection with a quartz arc tube designed to operate on a 600 volt commercial circuit, although it will be understood that the invention is not limited to this type of tube or to tubes operating at such high voltage, but it is also applicable to the relatively low potential mercury arc lamps of commerce.

60 It is generally known that a vapor arc device under certain conditions can be started by a high tension kick provided the temperature of the lamp lies between certain critical limits. This means that in a mercury quartz lamp the vaporization of the mercury 65 and consequent emission of electrons must be begun before the arc can be started. However, but very little heat is required to be applied to the cold cathode chamber to vaporize the mercury sufficiently for an arc to 70 be started by a high tension kick. As a 75 means of heating the cathode chamber an electric heater is simple to operate and occupies a comparatively small space.

80 In the present invention an electric heater is connected through suitable resistances as hereinafter further described, to the feed lines of the lamp.

85 In this invention a resistance and an inductance are connected in series to the negative terminal of the lamp in the same manner as with other direct current mercury arcs. A mercury switch, or shifter, is connected from a point between the inductance and the negative terminal of the lamp in series with a 90 resistance. This resistance can be used as a heater for the cathode chamber of the lamp. The shifter is mechanically connected to an armature operating in the inductance in the usual manner.

95 In one embodiment of this invention a part of the resistance in series with the shifter is in the form of an electric heating coil placed in a suitable manner about the cathode chamber and the rest in the usual form. In another 100

embodiment the heater is connected in parallel with the inductance and the arc, with other suitable resistances between the shifter and the heater.

5 The figure in the drawing shows a vertical sectional view of a quartz lamp having a liquid cathode and a heater therefor, and wiring connections in which the heater is connected in parallel with an inductance and the arc, and with resistance between the shifter and the heater.

10 In the drawing part 1 is a silica tube, 2 is an anode, 3 is a mercury cathode, 4 is a shifter, 5 is an inductance connected to the negative terminal of the lamp and which is also used as a solenoid to actuate the shifter 4 through the armature 17, the resistance 12 is connected in series with the cathode and the inductance, and is placed between the inductance 15 and the negative terminal of the feed in the manner usual to this type of lamp. The electric heating coil 6 is designed to surround the cathode chamber 18 and has one terminal connected between the inductance 5 and the resistance 12; its other terminal is connected to the positive feed of the lamp through a resistance 10, and through a switch 8. Between the point of connection of 6 to the positive feed and the anode a solenoid 9 is placed in 20 the anode lead. This solenoid 9 is designed to open switch 8 when an arc has been struck in the lamp. One side of the shifter 4 is connected between the cathode and the inductance 5; its other side is connected through a resistance 11 and to a variable connection on the resistance 10. By having a sliding connection on the resistance 10 it is possible to limit the maximum voltage that will be across the terminals of the shifter, the value of 25 10 of course being made such that suitable voltages will be obtained. For instance, the line voltage might be 500 volts and in such cases it would be desirable to have the shifter operate at a much lower voltage such for instance as 30 150 volts. By cutting in sufficient resistance in the shifter circuit at 10 the optimum voltage of the shifter can be obtained. Thus the shifter is connected in parallel with the heater circuit and part of its series resistance 35 10, and is also connected through the remainder of this resistance 10 and switch 8 to the positive side of the supply. The embodiment of my invention as shown operates as follows:

40 55 Upon closing a switch in the line the current flows through the switch 8 and through a part of resistance 10 where it divides, a part going through the rest of 10 and through the heater circuit and a part through the resistance 11 and through the shifter circuit. These two parts of the current flow together again at a point between the inductance 5 and the resistance 12. The solenoid 5 being energized the armature 17 is actuated and the 50 60 65 circuit through the shifter thereby broken.

On the breaking of the connection through 4 and therefore through 5 the magnetic field about the latter collapses and there is induced in it a high potential. In the meantime current has been flowing through the heating coil 6 and the mercury in the cathode chamber has begun to be heated. So, if there has been sufficient mercury vaporized at the time the high voltage kick is induced in the circuit of 5 an arc will be struck in the lamp. If the arc is not struck at this time the shifter 70 75 80 85 90 95 100 105 110 115 120 4 through force of gravity swings back into the circuit making position and the connection through 5 is re-established. This intermittent making and breaking of the circuit through 4 will continue until sufficient mercury has been vaporized for the striking of an arc in the lamp. When the arc is struck the current passing through the positive leads of the lamp will energize solenoid 9 which will operate switch 8 to break the circuit through the shifter and the heater and so leave them out of operation while the lamp is lighted. After the arc has been struck switch 24 which has been closed to short circuit half of the resistance 12 is opened to throw all of said resistance in series with the cathode.

I claim:

In an electric vapor-lamp, in combination, a liquid cathode, an anode, feed mains therefor, a solenoid in the positive lead of the lamp, an electric heater for the cathode connected on one side through a switch to the positive main, said switch being adapted to be opened by said solenoid when current is flowing through the lamp, an inductance connected on one side to the cathode and on the other through a resistance to the negative main, a connection from a point between said inductance and resistance to the other side of the heater, and a mercury switch connected on one side between the inductance and the cathode and on the other through a resistance to a sliding connection on a resistance between the electric heater and the switch in the positive side lead thereof, said mercury switch being mechanically connected to an armature operating in the inductance in the negative lead of the lamp.

Signed at Hoboken, in the county of Hudson, and State of New Jersey this 3rd day of July, A. D. 1925.

LEROY J. BUTTOLPH.
